UNITED STATES PATENT OFFICE

2,502,623

GUSSET CLAMP

James C. Holland, Los Angeles, Calif.

Application April 4, 1947, Serial No. 739,471

6 Claims. (Cl. 254—1)

1

The present invention relates to a clamp arranged to clamp, for example, a vertical frame member in a building structure and so formed that a convenient abutment is provided for engagement with a lifting jack whereby the structure may be lifted after the clamping structure is placed in position and the lifting jack is operated.

In the moving of building structures such as houses, garages and the like, it is desirable that the building structure be moved with the least amount of effort and with the least amount of damage to the building structure. It is, therefore, an object of the present invention to provide an improved means whereby these desiderata are achieved.

A specific object of the present invention is to provide an improved clamp which may easily be attached to a building structure in such a manner that the clamping structure firmly clamps the building structure and at the same time provides a convenient abutment for movement by a lifting object.

Yet, another specific object of the present invention is to provide an improved clamping structure for clamping a vertical frame member in a building structure characterized by the simplicity with which the clamping structure may be applied to provide good clamping engagement whereby the clamped building structure may be moved upon application of a force to the clamping structure itself.

The features of the present invention which are believed to be novel are set forth with particularity in the appended claims. This invention itself, both as to its organization and manner of operation, together with further objects and advantages thereof, may be best understood by reference to the following description taken in connection with the accompanying drawings in which:

Figure 1 is an end view of a garage partly broken away showing a combined clamping structure and abutment means incorporating the present invention mounted on one of the vertical frame members of the garage.

Figure 2 is a sectional view taken substantially on the line 2—2 of Figure 1.

Figure 3 is an exploded view in perspective of some of the elements shown in Figure 2; and

Figure 4 is a view similar to Figure 3 showing a modified clamping structure arranged to be maintained in clamped position by means of a bolt and nut as indicated in Figures 2 and 3.

The clamping structure 10 embodying the pres-

2

ent invention comprises two juxtaposed metal L-shaped members 11 and 12, each having integrally formed therewith on opposed surfaces, a plurality of cone shaped projections 13 and 13A, respectively arranged to be embedded in the wood frame member 14 upon tightening the nut 15 on the single bolt 16 which is arranged to pass through the openings 26 and 27 respectively in members 11 and 12. The free opposed ends of members 11 and 12 are maintained in spaced relationship by providing an inwardly extending projection 17 arranged to engage the inner face of the member 11.

The cone shaped members 13 and 14 which are pressed into the wooden frame member 14 are preferably hardened steel points welded to the members 11 and 12 respectively, while the stop members 17 may also be formed on the member 12 by welding operation or the like.

20 The clamp structure 10 is clamped on the wood vertical support member 14 as shown in Figure 1 so that the horizontal legs of the L-shaped members 11 and 12 may have a lifting force applied thereto, for example, from the lifting jack 20 which rests on the ground with a wooden bearing member 21 interposed between the lifting jack 20 and the horizontal legs of the L-shaped members 11 and 12.

In essence, the vertical legs of the L-shaped members 11 and 12 with the cone shaped members 13 and 13A respectively mounted thereon, provide good clamping engagement while the horizontal legs of the L-shaped members 11 and 12 provide a good abutment for the application thereto of lifting forces. Preferably, of course, the spacing of the free ends of the members 11 and 12 as determined by the length of the projection 17, is substantially equal to the thickness of the vertical lifting member 14 shown 40 in Figure 2.

One feature of the present invention is that but one bolt 16 and associated nut 15 is necessary to provide good clamping engagement. Preferably, the horizontal distance of the vertical legs of the L-shaped members 11 and 12 is substantially equal to the width of the wooden member 14 and the bolt 16 passes very close to the member 14 with the axis of the bolt 16 substantially midway between the vertical spacing of the extreme members 13 and 13A.

50 In the modified structure shown in Figure 4 wherein parts identical with those shown in Figures 1, 2 and 3 have identical reference numerals, the members 12 and 13 are each provided with an integrally formed reinforced bolt

and nut bearing member 30 (the bearing member on member 11 not being shown). The four spaced integrally formed rib members 31 served to strengthen the position of bearing member 30 on the member 12. Also, two spacers, 17A and 17B are mounted respectively on the ends of members 11 and 12 for serving the same purpose as does the member 17 in the arrangement shown in Figures 1 through 3. Instead of using but one member 17 extending the full distance between members 11 and 12, the two members 17A and 17B, each of equal length and of a length equal to one half the distance of member 17, are used in the modification shown in Figure 4.

While the particular embodiments of the present invention have been shown and described, it will be obvious to those skilled in the art that changes and modifications may be made without departing from this invention in its broader aspects and, therefore, the aim in the appended claims is to cover all such changes and modifications as fall within the true spirit and scope of this invention.

I claim:

1. In a structure arranged to transport building structures, the combination of a pair of L-shaped clamping members, wood gripping means mounted on opposed faces of the vertical legs of said L-shaped members, said vertical legs being arranged to have a supporting member of said structure sandwiched therebetween, releasable fastening means arranged to maintain said wood gripping means in engagement with said building structure, and the horizontal legs of said L-shaped members providing an abutment for the application thereto of lifting forces.

2. A combined clamp and lifting structure for use in transporting building structures comprising a pair of plate members arranged to have sandwiched therebetween a portion of said building structure, and releasable fastening means arranged to maintain said plate members in clamped engagement with said plate members having abutment means extending therefrom for the application thereto of lifting forces.

3. In a clamping structure arranged to clamp a building structure in the process of moving the same, a pair of L-shaped plates, wood gripping means mounted on opposed faces of the vertical legs of said L-shaped members, releasable fastening means arranged to engage and maintain the horizontal legs of said L-shaped members in clamped position wherein said wood engaging means is arranged to engage and sandwich a wooden support of said building structure therebetween, and an extension of the free end of one of the horizontal legs of one L-shaped

member extending in the direction of the juxtaposed horizontal leg of the other member to thereby provide a stop between the free ends of the horizontal legs of said L-shaped members.

4. A combined clamping and abutment means for use in the movement of building structures comprising, a pair of L-shaped plate members, wood gripping means mounted on opposed faces of the vertical legs of said L-shaped members and arranged to sandwich a wooden support of said building structure therebetween, stop means between the free ends of the horizontal legs of said L-shaped members, said stop means comprising an extension from the end of the free end of the horizontal leg of one of said members extending in the direction of the other juxtaposed horizontal leg, a bolt passing through the horizontal legs of said L-shaped members in proximity to the vertical legs of said L-shaped members and releasable fastening means on the end of said bolt.

5. The invention set forth in claim 4 characterized in that the holes through which the bolt passes are reinforced by integrally formed collars and webs on the exterior surfaces of said L-shaped members and said abutment means comprises inwardly extending extensions from the free ends of the horizontal legs of both of said L-shaped members.

6. A combined clamping and abutment means for use in the movement of building structures comprising a pair of plate members, wood gripping means on opposed surfaces of said plate members, an extension on each one of said plate members, stop means mounted between the free ends of said extensions, releasable fastening and moving means arranged to move said plate members towards one another to sandwich a supporting member of said building structure therebetween, and said extensions providing an exposed area for the application thereto of lifting forces.

JAMES C. HOLLAND.
